UNITED STATES PATENT OFFICE.

BENJAMIN F. CROW, OF ST. LOUIS, MISSOURI, ASSIGNOR TO THE BROWNELL & WIGHT CAR COMPANY, OF MISSOURI.

TROLLEY-SUPPORT FOR ELECTRIC CARS.

SPECIFICATION forming part of Letters Patent No. 448,505, dated March 17, 1891.

Application filed July 12, 1890. Serial No. 358,564. (No model.)

To all whom it may concern:

Be it known that I, BENJAMIN F. CROW, of the city of St. Louis, in the State of Missouri, have invented a certain new and useful Improvement in Trolley-Supports for Electric Cars, of which the following is a full, clear, and exact description, reference being had to the accompanying drawings, forming part of this specification.

10 My invention relates to an improved means for supporting the trolley of an electric car, whereby the weight is removed from the roof at the central portion of the car; and my invention consists in features of novelty hereinafter fully described, and pointed out in the claims.

Figure I is a top or plan view illustrative of my invention. Figure II is a side elevation showing a portion of the body of the car, 20 and showing the support to which my invention relates. Fig. III is a transverse section taken on line III-III, Fig. II.

Referring to the drawings, 1 represents a portion of the body of the car, and 2 the roof. 25 It has been customary heretofore to support the trolley of an electric railway directly on the roof of the car, which, if not made particularly strong for the purpose, and stronger than is otherwise necessary, becomes, after a 30 short time, injured and forced out of shape by the weight of the trolley.

The object of my invention is to provide a support which may be conveniently applied to any car, and by which the weight of the 35 trolley is removed from the central portion of a car-roof; and to this end my invention consists of a truss mounted on the car, composed of a compression member 3 and a tension member or members 4. I prefer to use 40 a compression member in the form of a board or strip of sufficient width to receive and support the trolley, which is represented by the circle 5 in Fig. I, this board or strip extending the length of the car-body, or about 45 the length of the car-body, as shown in Fig. II. The tension member or members of the truss are composed of one or more rods or straps of metal made to engage the ends of the compression member, as shown at 6. I 50 have shown two of the tension members, but it is evident that one alone of sufficient width or strength might be used.

7 represents blocks or brackets placed be-

tween the compression member and the top of the car, and which are preferably notched, 55 as shown in Fig. III, to receive the tension member or members of the truss, so that it or they will be elevated slightly above the roof of the car and not come in contact therewith, the object being to prevent the chafing on 60 the roof of the car, which would be incident to their bearing against the roof.

It will be seen that the outer ends of the truss are over the ends of the car-body, and the result is that instead of the weight of the 65 trolley being on the central portion of the car-roof it is transferred to the ends of the car, where the roof is permanently supported by the ends of the car-body, and thus the injury to the roof incident to supporting the 70 trolley directly thereon is avoided. An arrangement of this kind is exceedingly cheap and durable, and forms a permanent and strong support for the trolley, besides forming a convenient means for attaching the 75 trolley to the car. The blocks 7 serve to keep the tension and compression members of the truss the proper distance apart throughout the length of the truss, and thus serve as distance-blocks for the truss. 80

I claim as my invention—

1. In a trolley-support, in combination with a car-body, a truss composed of a compression member and a tension member mounted on the car, said tension member engaging the 85 ends of the compression member, substantially as set forth.

2. In a trolley-support, in combination with a car-body, a truss composed of the compression member and a tension member extending the length of the car-body, the ends 90 of the tension member being made to engage the ends of the compression member, substantially as set forth.

3. In a trolley-support, in combination with a car-body, a truss composed of the compression and tension members mounted on the car, said tension member engaging the ends 95 of the compression member, and the notched blocks or brackets located between the car-roof and compression member, substantially 100 as and for the purpose set forth.

BENJAMIN F. CROW.

In presence of—

THOS. KNIGHT,
E. S. KNIGHT.
